[57] **CLAIM**

The ornamental design for telephone network interface apparatus, as shown and described.

DESCRIPTION

FIG. 1 is a front perspective view of telephone network interface apparatus showing our new design with the cover shown in the open position;

FIG. 2 is a front elevational view thereof with the cover shown in the closed position;

FIG. 3 is a left side elevational view thereof with the cover shown in the closed position;

FIG. 4 is a right side elevational view thereof with the cover shown in the closed position;

FIG. 5 is a top plan view thereof with the cover shown in the closed position;

FIG. 6 is a bottom plan view thereof with the cover shown in the closed position; and

FIG. 7 is a rear elevational view thereof.

FIG. 1

FIG. 2

FIG. 3

FIG. 4

FIG. 5

FIG. 6

FIG. 7
